COMBINED COMB AND BRUSH OR SIMILAR ARTICLE

Lester R. Kahn, Jersey City, N. J., assignor to E. I. du Pont de Nemours and Company, Wilmington, Del., a corporation of Delaware

Application November 23, 1954, Serial No. 33,200

Term of patent 7 years

(Cl. D66—3)

Fig. 1

Fig. 2

Fig. 3

Figure 1 is a side view of the combined comb and brush or similar article embodying my new design.

Figure 4 is an exploded perspective view of the combined comb and brush or similar article indicating the manner in which the cover portion may be employed as a handle.

I claim:

The ornamental design for a combined comb and brush or similar article, substantially as shown and described.
